US0D1055187S

(12) **United States Design Patent** (10) Patent No.: **US D1,055,187 S**
Clarke et al. (45) Date of Patent: ** Dec. 24, 2024

(54) **GOLF CLUB HEAD**

(71) Applicant: **KARSTEN MANUFACTURING CORPORATION**, Phoenix, AZ (US)
(72) Inventors: **Jacob T. Clarke**, Apex, NC (US);
David A. Higdon, Cave Creek, AZ (US); **Anthony D. Serrano**, Phoenix, AZ (US)

(73) Assignee: **Karsten Manufacturing Corporation**, Phoenix, AZ (US)

(**) Term: **15 Years**

(21) Appl. No.: **29/866,647**

(22) Filed: **Sep. 21, 2022**

(51) LOC (14) Cl. **21-02**
(52) U.S. Cl. **USPC D21/743**

(58) **Field of Classification Search**

(57) **CLAIM**

The ornamental design for a golf club head as shown and described.

DESCRIPTION

FIG. 1 is a top perspective view of a golf club head;
FIG. 2 is a bottom perspective view of the golf club head of FIG. 1;
FIG. 3 is a top view of the golf club head of FIG. 1;
FIG. 4 is a bottom view of the golf club head of FIG. 1;
FIG. 5 is a front view of the golf club head of FIG. 1;
FIG. 6 is a rear view of the golf club head of FIG. 1;
FIG. 7 is a heel side view of the golf club head of FIG. 1;
and,
FIG. 8 is a toe side view of the golf club head of FIG. 1.
The broken lines shown on the drawings form no part of the claimed design.
